E. F. CLARK

SANITARY TOILET SEAT COVER

Filed March 31, 1923

INVENTOR.
ETHEL F. CLARK.
BY HER ATTORNEY.

James F. Williamson

UNITED STATES PATENT OFFICE.

ETHEL F. CLARK, OF SHOOKS, MINNESOTA.

SANITARY TOILET-SEAT COVER.

Application filed March 31, 1923. Serial No. 628,954.

To all whom it may concern:

Be it known that I, ETHEL F. CLARK, a citizen of the United States, residing at Shooks, in the county of Beltrami and State 5 of Minnesota, have invented certain new and useful Improvements in Sanitary Toilet-Seat Covers; and I do hereby declare the following to be a full, clear, and exact description of the invention, such as will enable others skilled in the art to which it 10 appertains to make and use the same.

This invention relates to a sanitary cover and particularly to such a cover adapted to be placed on a toilet seat. It is very desirable 15 in public places and hotels to have some sanitary cover for such seats which are frequently used by large numbers of different persons, as such covers insure sanitation and lessen the chances of contagion. 20 It has heretofore been suggested to use paper covers for this purpose but such use has been found not only wasteful but objectionable on account of these papers being deposited in the bowls and clogging up the 25 plumbing.

It is an object of this invention, therefore, to provide such a sanitary cover made of durable material so that the cover can be cleaned or sterilized and repeatedly used.

30 It is a further object of the invention to provide such a cover with simple and efficient holding and collecting means insuring that the covers will not be taken away.

These and other objects and advantages 35 of the invention will be fully set forth in the following description made in connection with the accompanying drawings in which like reference characters refer to the same parts throughout the different views, 40 and in which,

Fig. 1 is a view in elevation showing a cover in place and showing the receptacles therefor and the adjacent walls in section;

Fig. 2 is a plan view of one of the covers; 45 and

Fig. 3 is a vertical section taken on the line 3-3 of Fig. 2.

Referring to the drawings, a floor 1 is illustrated having secured thereto a toilet fixture 2 of usual construction having thereon the customary seat 3. The side wall 4 of the room is illustrated and has secured thereto by means of a suitable bracket 5 a box 50 or container 6 illustrated as of rectangular form. This box 6 has secured thereto a U-shaped rod 7, one vertical arm of which is

secured to the bottom of the container and which rod extends upward adjacent one wall of the container over the edge of the same and has its other arm projecting downwardly outside of said container substantially parallel to said wall. Said rod has an eyelet at the end of its outer arm to which is attached a flexible member 8, such as a chain, the lower end of which is secured to a suitable fastening in the bottom of a container 9 disposed below the top of the fixture 2. The container 9 is also illustrated as of rectangular form and the chain 8 extends substantially parallel and adjacent to one side 70 thereof.

The cover comprised in the invention is made of a sheet of gum rubber or other rubberlike material and is in the form of an oval piece 10 shaped substantially to fit 75 the seat 3 and provided with a central oval aperture 11 corresponding to the opening in the seat. The said cover has a projecting tab 12 at one side thereof in which is secured an eyelet 13 of any suitable style or 80 material.

The covers preferably are disposed in the container 6 threaded on the rod 7. When one of the covers is to be used the same is lifted from the container 6 and 85 moved along the rod 7 and chain 8 to proper position on the seat 3. After use the cover can be lifted to swing to position to be disposed in the receptacle 9. The covers 90 after being used are thus collected and can be readily sterilized by boiling, cleaning with various solutions or any of the well-known ways of sterilizing. After the covers have been so cleaned or sterilized 95 they can again be used. The rubber-like material is especially adapted for such an article and will readily take the shape of the seat and contact therewith will be unobjectionable. Besides being adapted to be used as described in hotels and public places, 100 such a cover could be carried by a traveler for private use.

From the above description it is seen that applicant has provided a simple and efficient article made from very desirable material and one which will have great utility. The fact that the covers can be repeatedly used will effect a great economy and the cost of the covers will be small.

It will, of course, be understood that various changes may be made in the form, details and proportions of the parts with-

out departing from the scope of applicant's invention, which, generally stated, consists in a device capable of carrying out the objects enumerated and such as described and 5 set forth in the appended claims.

What is claimed is:

1. The combination with a toilet seat, of a container disposed above said seat, a second container disposed below said seat sub- 10 stantially aligned with said first mentioned container, a relatively thin member disposed between said containers, a plurality of seat covers each having an eyelet secured in one side thereof threaded on said member so 15 that the same can be stored in the upper container and moved to a position on said seat and then disposed in said lower container.
2. A sanitary toilet seat cover apparatus comprising an upper container disposed 20 above said seat, a U-shaped rod secured therein extending along one side thereof over the edge of said side and down along the exterior thereof, a flexible member se- 25 cured to the end of said rod and extending downward from the outer end thereof, a

lower container disposed below said seat, said flexible member being secured in said latter container and a plurality of seat covers having eyelets secured in the sides thereof and threaded on said flexible member and rod so that the same can be stored in the upper container and moved to position on said seat and then disposed in said lower container. 30

3. The combination with a toilet seat, of a container disposed above said seat, a second container below said seat, a relatively thin member connecting said containers having a flexible portion disposed adjacent said seat and a plurality of seat covers having 35 eyelets secured in the sides thereof and threaded on said member so that the same can be stored in the upper container and moved to a position on said seat and then disposed in said lower container, said 40 flexible portion of said member permitting adjustment in the cover when on said seat.

In testimony whereof I affix my signature.

ETHEL F. CLARK.
